Orafresh Tongue Cleaning advertisement 1997.

* cited by examiner

Primary Examiner—Ian Simmons(74) Attorney, Agent, or Firm—Sand & Sebolt(57) CLAIM

The ornamental design for handle for tongue cleaning device, as shown and described.

DESCRIPTION

FIG. 1 is top plan view of a handle for a tongue cleaning device showing our new design.

FIG. 2 is a front elevation view FIG. 1; and,

FIG. 3 is left side elevation view of FIG. 1.

The broken lines are for illustrative purposes only and form no part of the claimed design.
